ATTORNEY

UNITED STATES PATENT OFFICE.

WARREN S. BELDING, OF PHILIPSBURG, PENNSYLVANIA.

RIFLE-CLEANING-ROD TIP.

Application filed August 12, 1924. Serial No. 731,560.

To all whom it may concern:

Be it known that I, WARREN S. BELDING, a citizen of the United States of America, residing at Philipsburg, Center County, Pennsylvania, have invented new and useful Improvements in Rifle-Cleaning-Rod Tips, of which the following is a specification.

This invention relates to improvements in or connected with cleaning rods for rifles and other firing pieces.

As is well known modern rifle cleaning is done from the breach, not from the muzzle. This is to avoid wearing the edge of the muzzle. Bolt action rifles are difficult to clean from the breach because after removing the bolt there remains the case around the bolt, usually called the receiver, which is usually from 4 to 6 inches in length. In passing through this receiver the cleaning patch of cloth is easily dislodged from the tip of the cleaning rod.

With the object of avoiding the displacement of the cleaning patch, the present invention provides a tip for a cleaning rod having a sharp point on which the patch can be stabbed prior to its entry into the receiver and which tip at the same time is provided with means whereby, when the cleaning rod is retracted, the patch will still be held firmly in position.

Other objects and advantages of the invention will be apparent from the embodiment of the invention now to be described in conjunction with the accompanying drawings, in which—

Figure 1 is a side view of a tip for a cleaning rod constructed according to the present invention;

Fig. 2 is a similar view of Fig. 1 showing the tip on a considerably enlarged scale; and,

Fig. 3 is a cross section taken on the line 3—3 of Fig. 2 looking in the direction of the arrows.

As will be seen from the drawings the tip, the subject-matter of the present invention, comprises a reduced end portion 1 provided with a screw thread 2 by means of which it can be attached to and form part of a cleaning rod of the usual construction. Integral with and beyond said reduced portion 1 the tip is of increased diameter for a por-

tion of its length, as indicated at 3, which diameter is preferably the same as that usually given to cleaning rods, that is to say, something less than the diameter of the bore of the rifle through which it is intended to be passed. Integral with and beyond the portion 3, the tip for some distance is made of reduced diameter, as at 4, and projecting from this reduced portion are a plurality of integral spaced-apart rings or collars 5. Beyond these collars the tip is again given its normal diameter in the form of an integral cap 6. The spaces between the different collars and the space between the cap and the collar adjacent thereto are preferably equal but may be varied as may be found necessary or desirable. Projecting from the cap 6 is an integral centrally disposed pin 7 provided with a sharp point 8 on which the cleaning patch which, for example, may take the form of the usual piece of flannel, may be stabbed; thus the patch is firmly secured in place by the aid of said point and is so held in passing the rod through the receiver of a rifle and subsequently through the bore thereof.

The spaced-apart rings or collars 5 are provided for gripping the patch on the movement of the tip in the opposite direction through the bore and breach of the rifle, that is to say, on its retraction. The present tip therefore provides means whereby the patch can be held in place on the tip during the movement of the cleaning rod in both the directions, that is to say, as it is pushed forward through the receiver and thence into the bore of the rifle and on its movement in the opposite direction to withdraw it first from the bore and then from the receiver.

The diameter of the cap 6 is preferably that of the diameter of the bore of the rifle to be cleaned less twice the thickness of the cleaning patch. This should be obvious because when the patch is stabbed on the point 8 and is then folded back over the cap 6 and over one or more of the collars 5 it will completely encircle the cap and therefore two layers thereof will be interposed between the bore and said cap, that is to say, one layer at either end of a line passing diametrically through the longitudinal axis of the tip.

The collars 5 are preferably made of a diameter slightly less than the diameter of the cap, for example, they may be made the diameter of the bore of the rifle minus three times the thickness of the cleaning patch.

By the above construction it has been found in practice that the patch is kept nicely and evenly in contact with the walls of the bore of a rifle during its movement in both directions therethrough, with the result that the cleaning of said bore can be effected in a very efficient manner with a minimum of strokes, damage to the bore being thus avoided.

Having now described my invention, what I claim and desire to secure by Letters Patent is:

1. In a rifle-cleaning rod tip, a cap at one extremity of said tip, a centrally disposed pointed pin projecting from one face of said cap, a reduced portion extending from the opposite face of said cap, a plurality of spaced-apart collars formed on said reduced portion, and means for securing said tip to a cleaning rod at the other extremity of said tip.

2. In a rifle cleaning rod tip, a cap at one extremity of said tip, a centrally disposed pointed pin projecting from one face of said cap, a reduced portion extending from the opposite face of said cap, a plurality of spaced-apart collars formed on said reduced portion, and means for securing said tip to a cleaning rod at the other extremity of said tip, said cap having a diameter equal to the diameter of the rifle bore less twice the

thickness of the cleaning patch and said collars having a diameter equal to the diameter of the rifle bore less thrice the thickness of said patch.

3. A tip for a cleaning rod comprising a circular piece of metal being for a part of its length of reduced diameter, a plurality of spaced-apart circular collars formed on said reduced portion, a circular and integral cap formed beyond said collars, an integral pin having a sharp point projecting from one face of said cap and forming one extremity of the tip and a reduced screw-threaded portion at the other extremity of the tip whereby the tip can be secured to the remainder of the rod.

4. A tip for cleaning rods comprising a circular piece of metal having a cap of the diameter of a rifle less twice the thickness of the usual patch, a pin having a sharp point formed integral with and projecting from one face of said cap, a plurality of spaced-apart collars formed integral with and projecting from a reduced portion of said tip, and means for connecting said tip to the remainder of a cleaning rod, said pin being adapted to hold the patch in place during its movement through the receiver and bore of the rifle and said collars being adapted to hold said patch in position during the movement of the tip through the bore and receiver in the opposite direction.

In testimony whereof I have signed my name to this specification.

WARREN S. BELDING.
